US00D855998S

(12) **United States Design Patent** (10) **Patent No.:** **US D855,998 S**
(45) **Date of Patent:** ** *Aug. 13, 2019

(54) **TOOTHBRUSH HEAD**

(71) Applicant: **The Gillette Company LLC**, Boston, MA (US)

(72) Inventors: **Christine Hielscher**, Frankfurt (DE); **Sarah Mote**, Frankfurt (DE); **Dominik Langhammer**, Frankfurt (DE); **Tilmann Winkler**, Kronberg (DE); **Aycan Senturk-Andersson**, Frankfurt (DE); **Benedikt Heil**, Friedberg (DE)

(73) Assignee: **THE GILLETTE COMPANY LLC**, Boston, MA (US)

(*) Notice: This patent is subject to a terminal disclaimer.

(**) Term: **15 Years**

(21) Appl. No.: **29/618,559**

(22) Filed: **Sep. 21, 2017**

(30) **Foreign Application Priority Data**

Mar. 22, 2017 (WO) 2823801

(51) **LOC (12) Cl.** **04-02**

(52) **U.S. Cl.** ..... **USPC** **D4/104**

(58) **Field of Classification Search**

(57) **CLAIM**

The ornamental design for a toothbrush head, as shown and described.

DESCRIPTION

FIG. 1 is a perspective view of a toothbrush head;

FIG. 2 is a front elevation view thereof;

FIG. 3 is a right side elevation view thereof;

FIG. 4 is a rear elevation view thereof;

FIG. 5 is a left side elevation view thereof;

FIG. 6 is a top plan view thereof; and,

FIG. 7 is a bottom plan view thereof.

The broken lines in the drawings illustrate features of the toothbrush that form no part of the claimed design.
